APPARATUS FOR REFORMING CAN BODIES

James A. Gray, San Francisco, Calif., assignor to
American Can Company, New York, N. Y., a
corporation of New Jersey

Application August 13, 1932, Serial No. 628,701

19 Claims. (Cl. 153—32)

The present invention relates to an apparatus for reforming can bodies from a preliminary flat shape into a cylindrical or other final form such as is universally found in the tin can of commerce.

In the manufacture of tin cans it is often desirable that economy of packing and shipping be provided for and this may be done by shipping the can bodies while in a preliminary flat or flattened stage. Such flattened bodies are adapted to be first reformed or rounded into the final body shape and are then supplied with an end or bottom to produce the desired can. The apparatus of the present invention is for efficiently and rapidly effecting this reforming stage in the can's manufacture. The present invention concerns itself entirely with the conversion of the flattened or flat can bodies into cylindrical or other desired shape and this without regard to the manufacture or provision of the bodies in flattened condition.

The principal object of the present invention is the provision of an apparatus for rapidly reforming can bodies in substantially continuous successive steps by feeding the bodies from element to element through a reforming matrix which is of substantially flattened oval shape in cross section at the receiving end and which terminates in a discharge opening of the desired cylindrical form.

An important object of the invention is the provision of a prebending or bowing station in an apparatus designed to feed flat can bodies from a magazine and into and through a reforming matrix, the prebending operation bowing parts of the can body as an incidental step to the reforming action of the matrix reforming elements.

A further object of the invention is the provision of an apparatus for reforming flat can bodies wherein a series of reforming rollers is utilized in a manner providing a tapered matrix through which the can bodies are passed, the shape, size, position and movement of the reforming rollers drawing the bodies successively through each reforming unit, the passing of the bodies into each unit being at a different speed of travel from the lineal travel of the engaging roller surfaces, this feature insuring the proper separation of the can bodies throughout the reforming operation.

An important object of the invention is the provision of improved feeding devices in an apparatus of the character described, for separating a single flat can body from a stack of can bodies in a supply magazine and for moving it into a pre-

bending or bowing station where it is accurately centered and then subjected to a preliminary bending operation prior to being brought into position for its travel through the reforming matrix.

Numerous other objects and advantages of the invention will be apparent as it is better understood from the following description, which, taken in connection with the accompanying drawings, discloses a preferred embodiment thereof.

Referring to the drawings:

Figure 1 is a plan view partially broken away of a preferred form of apparatus;

Fig. 2 is a longitudinal sectional view taken substantially along the line 2—2 in Fig. 1;

Fig. 3 is an enlarged sectional view taken substantially along the line 3—3 in Fig. 1 and illustrating the mechanism at the prebending or bowing station;

Fig. 4 is an enlarged transverse sectional view taken substantially along the broken line 4—4 in Fig. 1;

Fig. 5 is an enlarged transverse sectional view taken substantially along the broken line 5—5 in Fig. 1;

Fig. 6 is an enlarged transverse sectional view taken substantially along the broken line 6—6 in Fig. 1;

Fig. 7, 8 and 9 are transverse sectional details taken substantially along the broken line 7—7 in Fig. 6, the three views illustrating different positions of a part of the mechanism at the prebending station; and

Figs. 10, 11 and 12 are fragmentary schematic details, shown generally in elevation, and illustrating the flattened can body in its relation to parts of the prebending mechanism as assumed respectively in the steps of operation shown in Figs. 7, 8 and 9.

The apparatus illustrated in the drawings discloses a preferred embodiment of the invention in which flat or flattened can bodies are stored in stack formation within a magazine. A reciprocating feeding device operating transversely of the magazine shears the lowermost body from the bottom of the stack and moves it into a station for a prebending operation.

The flat or flattened can body handled in this way has relatively flat side parts joined by sharply curved connecting parts. Spring pressed dogs are used with the reciprocating feeding device and these engage one of the rounded connecting curved parts of the can body as an incident to removal from the stack. Using the curved part in this manner insures positive engagement of a single can body irrespective of

whether the flat parts of the body are close together as when collapsed or whether the body is more open.

At the prebending station the forward sharply curved part of the body, opposite to that engaged by the feeding dogs, is engaged by oscillating fingers which are cam controlled to shift back to recheck the can body and bring it into proper alignment. A pair of spaced slide members is located at this station, one member of the pair being adjacent each open end of the aligned can body.

Each slide is cam operated and carries an anvil and a pair of centering spears and both spears and anvils are pointed at their inner ends. As the slide members move toward each other the two centering spears on each side enter into the opposed sharply curved connecting body parts. In the innermost position of the slides the two opposed anvils are fully inserted within the open ends of the can body.

Each slide carries an upper and lower die member spaced respectively above and beneath an associated anvil. The die members are also cam operated and when moved close upon the engaged open ends of the can body, squeeze it against the anvils and outwardly bow the edges of the flat parts of the body. This effects a prebending of the body. Upon the next reciprocation of the feeding devices spring held dogs spaced in front of the feeding dogs, engage the partially opened can body and move it laterally into axial alignment with a reforming matrix.

The reforming matrix is made up of a series of pairs of reforming rollers, the rollers of each pair being spaced from and arranged on opposite sides of the longitudinal axis of the matrix. These rollers rotate and are formed with concave surfaces adapted to form a concave matrix to engage the outside surface of the flattened can body.

The can body with its slightly bowed open sides is moved at right angles to its former travel to introduce it into the matrix formed by the reforming rollers by engagement with a lug carried by a conveyor chain. The upper run of this chain moves in a horizontal plane, the chain passing over vertically disposed sprockets. The upper run moves in between bottom flanges of each pair of spaced reforming rollers.

The can body upon being engaged by the lug of the conveyor chain is first carried through a series of spaced guiding rollers. These rollers engage outside of the sharply curved parts of the body and guide the body along a straight line path of travel into the first pair of reforming rollers.

The concave walls of the first pair of reforming rollers present an entrance opening or mouth for the reforming matrix which is substantially oval in shape. The opposed side walls of the rollers are slightly closer together than the engaging walls of the guiding rollers and a partial bending of the can body results. In other words, the body is altered in cross section from the flattened oval shape into a more rounded shape as it passes through the rollers.

These rollers are rotated at a uniform speed which is slightly greater than the conveyor chain speed and this increased speed causes the rollers to pick up and move the can body so that it momentarily leaves the engaged lug of the conveyor chain. As soon as the can body has passed through the first pair of reforming rollers it pauses in its travel.

75. When the chain lug catches up it pushes the

can body into the next set of rollers which again draw the body forward further bending or reforming it. In like manner the body is fed to each pair of rollers which successively engage and further reform it. The concave walls of the last pair of rollers present a true circular pass and the can body upon emerging from them is in its final cylindrical form.

5. The principal parts of the apparatus are carried in and on a frame or casing 21 (Figs. 1 and 2) 10 which is supported by legs 22. The reforming roller section of the machine, which covers an area over half the entire extent, is supported upon a casing cover 23 which rests upon the casing 21. The casing is also provided with a table section 15 24 which extends in a horizontal plane below the plane of the cover 23.

The table 24 at its inner end 25 (Fig. 3) supports a flange 26 of the casing cover 23. The magazine for the flattened can bodies and the 20 prebending can body devices are both carried on the table section 24. A magazine frame 31 is provided for directly supporting these parts and is formed with a horizontal table top section.

The magazine for the flattened can bodies (the 25 bodies being designated by the numeral 35) comprises spaced vertically extending brackets 36 (Figs. 1, 2 and 4) which are mounted upon and secured to the magazine frame 31 by bolts 37. This constitutes station A. The inner vertical 30 faces of the magazine brackets 36 are vertically grooved at 38 to provide clearance for free vertical movement of the flattened can bodies while retaining them in the stack. The can bodies 35 are formed with flat side parts 41 (Figs. 4 and 10) 35 which are joined by sharply curved connecting parts 42.

Two grooves 45 (Figs. 1 and 3) are formed in the flat table part of the magazine frame 31 to provide a working support for the can body feeding 40 devices and these grooves extend transversely of and beneath the magazine. A pair of feed bars 46 (see also Figs. 4 and 5) are located in the grooves 45 and move back and forth to effect the removal of a single flattened can body 35 from 45 the magazine and to effect a transfer of the body into the reforming station. The bars 46 at their rear ends are secured to a block 47 which moves within a slot 48 cut in the magazine frame 31.

The feed bars 46 are moved back and forth 50 by connection with a continuously rotating shaft 67, the block 47 being pivotally connected at 49 to one end of a link 51 which is pivotally connected at 52 to the upper end of a lever 53. Lever 53 is mounted for oscillation on a shaft 54 which is 55 carried by a bracket 55 bolted on the casing 21.

The lever 53 is pivotally connected at 56 to a ball and socket joint unit 62 which is threadedly secured to one end of a connecting rod 63. This rod carries a similar ball and socket 60 joint unit 64 carried on a bolt 65 (Fig. 1) which is secured to a disc 66 (see also Fig. 4) carried on one end of the horizontal shaft 67. The shaft 67 extends at a slight angle to the center line of the casing 21 and is associated with the reforming 65 matrix as will be more fully disclosed. Shaft 67 is journalled in a bracket 68 mounted on the table 24 and in split bearings 69 formed in the casing 21 and the cover 23.

The shaft 67 carries a spiral gear 71 (Fig. 1) 70 which meshes with a similar gear located directly beneath and secured to a horizontal drive shaft 72 which extends cross wise of the casing 21 and is journalled in bearings 73 formed in its side walls. The shaft 72 is rotated in any suitable manner as 75

by application of power to a drive pulley 74 carried on one end.

The eccentric mounting of the bolt 65 on the disc 66 effects a crank motion which imparts reciprocating movement to the rod 63, the lever 53 and the feed bars 46.

Each bar 46 carries a fixed feeding dog or finger block 75 (Figs. 1 and 4) which is formed with a curved front end 76. When the feed bars 46 and fingers 75 are in the rear position, this being at the end of the back stroke of the feeding device (Fig. 5) the forward edges 76 are alongside and directly back of the lowermost flattened can body 35 resting in the magazine. This lowermost body supports the rest of the stack of bodies and at such time rests directly upon the upper surface of the table part of the magazine frame.

Upon forward movement of the feed bars 46 the forward edges 76 of the feeding dogs or blocks 75 engage behind the sharply curved part 42 of the lowermost body and move it laterally or toward the left (Fig. 5). The lower ends of the magazine walls 38 extend downwardly a distance sufficient to prevent similar movement of the other superimposed can bodies resting in the magazine. The remaining bodies in the stack are then supported upon the top surface of the blocks 75 as illustrated in Fig. 4.

At the forward end of the stroke the blocks 75 position the separated can body at the prebending station B. During this movement of a can body 35 from the magazine (station A) to the prebending station B it is guided in a straight line between side plates 77 (Figs. 1 and 4) secured at 78 to the magazine frame. A horizontal top guide bar 79 is mounted above the path of travel and prevents upward displacement. This bar is carried on cross straps 81 carried on certain frame parts of the prebending station.

A checking device now operates to engage the front sharply rounded edge 42 of the can body and push it back against the finger block faces 76. The checking device comprises fingers 85 (Figs. 4, 5 and 7) which are secured to a horizontal rock shaft 86 journaled for oscillation in depending lugs 87 formed in the magazine frame 31. Each finger 85 is provided with a notch 88 and it is this part of the finger that engages the forward curved part 42 of the body when the checking takes place. In this action the shaft 86 is moved to bring the fingers 85 from the idle position illustrated in Fig. 5 into the checking position illustrated in Fig. 4.

Oscillation of the shaft 86 is effected by a cam, gear and rack unit which comprises a gear pinion 91 secured to the shaft 86 and located between the fingers 85. The teeth of this pinion are engaged by rack teeth 92 formed in the upper end of a cam yoke 93. The lower end of the yoke straddles a horizontal shaft 94.

A cam 95 is mounted on the shaft 94 adjacent the yoke and engages a cam roller 96 loosely mounted on a stud 97 carried by the yoke 93. A spring 98 is interposed between the lower end of the yoke 93 and a supporting eye 99 carried in the table part 24 of the casing 21.

The shaft 94 is a companion to the shaft 67 and also extends in a horizontal plane and lengthwise of the casing but on the opposite side of the center line. This shaft is also located at a slight angle to the center line and is journaled for rotation in split bearings 101 (Figs. 1, 2 and 3) formed in the casing 21 and the cover 23 and in a bearing 102 formed in a bracket 103 carried on the table part 24.

The shaft 94, like its companion shaft 67, receives rotation from the drive shaft 72 and for this purpose carries a spiral gear 105 which meshes with a spiral gear 106 mounted on the shaft 72. The non-parallel position of the shafts allows for proper location of driving gears imparting rotation to the different rollers of the reforming matrix. This will be more evident as the description proceeds.

The can body in its centered position laterally between the feeding dogs 75 and the fingers 85 is longitudinally centered between a pair of holding and bending die units and is ready for the first of the operations at the prebending station.

The elements of the holding and bending die units are carried on a pair of spaced slides 110 (Figs. 3 and 6) which are located on opposite sides of the open ends of the can body. These slides have movement toward and away from the can body and slide within guideways 111 formed in the magazine frame 31.

The elements carried by the slides 110 include anvils on which the can body is positioned, centering devices which enter into the can body at its opposite open ends and guide and center it on the anvils, and bending dies which cooperate with the anvils and impress an outward bow shaped bend to its edges. These parts will now be described in detail.

Each slide 110 is moved back and forth under a cam control and for this purpose a boss 112 projects downwardly from the lower face of the slide and carries a stud 113 on which a cam roller 114 is rotatably mounted. This roller operates in a groove 115 of a barrel cam 116 mounted upon shaft 94 and keyed to the shaft 94.

The slides 110 move outwardly into open position as a flattened can body is brought into place and inwardly to effect the bending operation. The slides 110 are retained in the grooves 111 by plates 121 mounted upon the magazine frame 31 and projecting over and on top of the side edges of the slides. The magazine frame 31 is cut away at 122 to allow clearance for the sliding movement of the bosses 112.

An anvil 125 (Figs. 3, 5, 7 and 11) is secured by bolts 126 on the front or inner end of each slide 110 and is formed with a tapered or pointed end 127. Each slide 110 also carries a pair of spaced can centering spears 128 which project ahead of the pointed end 127 of each anvil. Each spear is formed with a pointed end 129. During the inward movement of the slides the spears pass into clearance openings 131 formed in the side guide members 77 and through similar clearance openings 132 formed in other side plates 133 and 134 arranged in alignment with the members 77 and on the opposite side of the prebending station. The plates 133, 134 are suitably mounted upon stationary parts carried by the magazine frame table.

The centering spears 128 move into the rounded curved parts 42 of the flat can body as it rests at the prebending station, the pair of spears on each slide 110 moving toward those on the other slide. The entering position is illustrated in Figs. 7 and 10. The centered position of the spears in opposite sides of the open ends of the flattened can body is illustrated in Figs. 8 and 11.

Continued movement of the slides 110 brings the pointed ends 127 of the opposed anvils 125 into the open ends of the can body and into the position illustrated in Figs. 9 and 12. This position is assumed when the slides 110 reach their innermost travel. The slides then remain stationary for the prebending operation.

The bending die members previously referred to comprise an upper die arm 135 (Figs. 1, 3 and 7) and a lower die arm 136, there being one upper and one lower arm on each slide 110. The upper arm 135 is pivoted on a pin 137 which is carried in a pair of spaced lugs 138 projecting upwardly from the slide. In a similar manner the lower arm 136 is pivoted on a pin 141 carried in spaced lugs 142 which are projected downwardly from the body of the slide. Each arm 135 carries a bending die 143 and a similar die 145 is carried on the inner end of the arm 136.

The dies 143, 145 are in separated position (Figs. 7, 8 and 10) during the positioning of the can body upon the anvils 125 but are adapted to be moved by movement of the arms 135, 136. For this purpose arm 135 is formed with an extension 148 which projects at right angles to the main body of the arm and extends over and behind the slide 110.

A spring 149 is interposed between this extension 148 of the arm and a connecting eye 151 carried on the lug 142. This spring normally holds the forward end of the arm 135 in raised position and the die 143 separated from and directly above its associated anvil 125. A setscrew 152 threadedly engaging the arm 135 provides a stop by engaging the upper surface of the slide 110 and limits the amount of the pivotal movement of the arm on its pin 137.

A spring 155 is interposed between the lower surface of the slide 110 and the arm 136 and exerts a force which normally holds the arm in its lowered position with the die 145 separated from and directly beneath its associated anvil 125. A setscrew 156 carried in the arm 136 provides a stop by engaging the lower surface of the slide 110 and limits the amount of pivotal movement of the arm on its pin 137.

Each cam 116 (Figs. 3 and 9) is formed with a lateral web 161 which projects from its outer face and is slotted at 162 to provide clearance for a roller 163 pivotally mounted on a pin 164 carried in the web. At a point in each rotation of the cam 116, the roller 163 is brought adjacent the extension 148 of the arm 135 and engages a striking block 165 secured by a bolt 166 to the lower end of the extension and causes the arm 135 to rock on its pivot 137.

A second web 168 is formed on the inner face of each cam 116 and is directly opposite to the web 161. This web 168 is slotted at 169 to provide clearance for a roller 171 which is rotatably mounted upon a horizontal pin 172 carried in the web. During engagement of the roller 163 with the block 165 just described, the roller 171 is moving adjacent the lower arm 136 and at such time engages the under surface of the arm, causing it to move on its pivot 141 against the action of the spring 155.

These simultaneous movements of the arms 135, 136 cause their respective bending dies 143, 145 to engage the edges of the flat portions 41 of the can body as it rests upon the anvils 125 and to impress an outward bowed form in the can body. This position of the dies and associated parts is illustrated in Fig. 12.

It will be observed that the upper face of each anvil 125 is slightly curved as at 175 and that the lower face of the anvil is similarly curved as at 176. The body engaging surfaces of the dies 143 are also curved as at 177 and this curved surface cooperates with the surface 175 to effect the proper bowing of the can body. In a similar way the upper engaging surface of the die 145 is curved

as at 178 to correspond with the surface 176 of the anvil, and these cooperating curved surfaces produce the bowed form of the can body, illustrated in Fig. 12.

The can body is now in condition for reforming the bowed shape of the body, holding its flat walls 41 separated so that it will be more accurately and more evenly opened when passed through the reforming matrix. Upon separation of the dies and withdrawal of the anvils and centering spear 101 members, the body is redeposited upon the table of the magazine frame 31.

At this time the feed bars 46 are in their rear position and the centering fingers 85 are in lowered position, as illustrated in Fig. 5.

Each feed bar 46 is slotted at its forward end as at 185 and a spring held dog 186 is located in the forward end of each slot. This dog is pivoted on a pin 187 and its rear end normally engages the floor of the slot, being held in such position by a spring 188. In this position a forward curved end 189 is raised and is directly behind the rear curved edge 42 of the bowed can body.

On the next forward movement of the feed bars 46 which immediately follows, the dogs 186 engage the bowed can body and move it to the left (into position C, Fig. 5) and out of the prebending station B as the finger blocks 75 bring the next can body into position at this station.

During this movement the can body is guided between the members 133, 134 (Fig. 1) and is held down by the top guide bar 79 which extends all of the distance between stations A and C. A stop plate 190 is located at the end of this travel and properly positions the can body at station C. The plate 190 is secured to the casing part 24 and carries the ends of the guide members 79, 133, 134.

At station C the can body is in alignment with the reforming matrix of the apparatus and is on the longitudinal center of the reforming roller organization which makes up this matrix. A continuously moving conveyor chain operates longitudinally of the reforming matrix and along its line of center and assists in the proper feeding movement of the can bodies into each pair or set of rollers.

This conveyor chain (designated by the numeral 191, Figs. 1, 2, 3 and 4) operates over an idler sprocket 192 at the entrance end of the reforming matrix and a drive sprocket 193 at the discharge end. The upper or feeding run of the chain 191 passes over the frame cover 23 and directly below the reforming rollers and its lower or return run passes through and inside of the casing 21.

Spaced lugs 194 are carried on the chain 191 and as the can body is brought into position at station C it moves laterally of and between two adjacent lugs. These lugs are spaced apart a distance in excess of the can body height and the lug directly back of the can body at the time immediately engages behind one open edge and advances it toward the reforming matrix, this movement being at right angles to the can body path between stations A, B and C.

The sprocket 192 is mounted on a stud 195 which is supported in a bracket 196 mounted upon and secured by bolts 197 to the table section 24 of the casing 21. The drive sprocket 193 is keyed to a horizontal shaft 198 which is journaled in a bearing 199 formed in a bracket 201 bolted to the side of the casing 21. The shaft 198 also carries a bevel gear 202 which meshes with a bevel pinion 203 carried on the end of the shaft 75.

94. This gear connection continuously moves the chain 191 in its path of travel.

The casing 21 is formed with a raised rectangular section 211 (Figs. 1 and 2) which provides 5 a support for three pairs of guiding rollers 212 at a station D. These rollers are idly mounted upon vertical studs 213 carried by the frame part 211. The moving conveyor chain 191 carries the 10 can body through these guiding rollers, the lug 10 of the chain resting against the body edge. Concave faces 214 formed in the rollers engage the curved parts 42 of the can body and while turning on their axes, hold it in bowed and partially opened position.

15 The first pair of rollers 212 may be further spaced from one another than the intermediate and last pair of rollers if desired in order to more fully bow the can bodies and bring their curved parts closer together before introduction into the 20 reforming rollers. When this is done the guiding rollers 221 function as reforming rollers.

The reforming matrix extends from a station E into a station F (Figs. 1 and 2). The drawings illustrate five pairs or sets of reforming rollers 25 for the reforming matrix. All of these rollers are similarly mounted and each roller of a pair or set is located on opposite sides of the longitudinal axis of the matrix from its associated roller.

30 The first pair of reforming rollers, designated by the numeral 221 (see also Fig. 4) is located directly in front of the last pair of guide rollers 212. Rollers 221 are formed with concave surfaces 222 and the spaced opposed surfaces of the rollers provide a substantially flat oval opening 35 or entrance for the reforming matrix. It is into this oval mouth that the bowed can body is moved by the conveyor chain 191.

The three intermediate pairs of reforming rollers are designated by the numeral 223 and the 40 final pair of rollers by the numeral 224. All of these rollers are also formed with concave surfaces 222.

45 Each pair of rollers beginning with those adjacent the entrance rollers 221 and then taking adjacent sets in order, are mounted upon vertical axes which are spaced closer to each other. The axes of the final rollers 224 are the closest together. This accounts for the non-parallel position of the shafts 61, 94 previously referred to and permits the axes of the shafts passing 50 parallel with a vertical plane which takes in the axes of the reforming rollers. The entrance rollers 221 are shorter in height than any of the other rollers and each pair progressively increases in body height toward the exit end of the matrix.

55 The space between the concave surfaces of each set of rollers therefore provides a different cross section to the reforming matrix which, excepting the final rollers, is of oval shape with the vertical or short axes increasing as the horizontal or long axes decrease. The concave surfaces of the final rollers 224 present a true circle for the discharge end of the matrix.

60 As the can body moves through the reforming matrix it successively engages the concave surfaces of the pairs of spaced rollers and moves through the rollers with the outside body wall surface engaged by the concave roller surfaces 65 222. The shape of the can body during this passage through the matrix progressively changes from the oval form into the final cylindrical form.

65 The passage of the can body through the reforming rollers takes place in a series of intermittent steps of body travel. Each roller rotates

70 at a speed of travel which produces a lineal travel of the concave surfaces 222 in excess of the lineal travel of the conveyor chain 191. The result of this difference in travel speed between roller and chain causes each opposed roller set upon engaging the outer surface of the can body to draw the body through the rollers at a speed which moves it way from the chain lug 194.

75 As soon as each set of rotating rollers has carried the can body therethrough the body comes 10 to a momentary pause in its travel until the lug 194 on the chain catches up with the body. When this takes place the can body is again moved forward by the chain and its forward open end is inserted into the next pair of reforming rollers. 15

80 Each reforming roller 221, 223, 224 is mounted upon a vertical shaft 231 which is journaled in bearings 232 formed in the cover plate 23. Each shaft 231 carries a spiral gear 235 which meshes with a similar gear 236 located upon either the 20 shaft 61 or the shaft 94. These spiral gear sets insure the proper rotation of the rollers to perform the reforming action just described.

85 The upper flange of each reforming roller is of a diameter to cause it to practically touch the 25 upper flange of the associated roller of the set. Its lower flange, however, is of smaller diameter and this leaves a space between the peripheries of the lower flanges of each roller set. The lugs 194 of the conveyor chain 191 pass in between 30 the rollers and through the clearance space between the lower flanges.

90 As the can body passes through each set of 35 rollers and as it comes to the momentary pause described awaiting the lug 194 of the chain 191, it is held against displacement by guide walls 241 formed in horizontal plates 242 bolted to and resting upon the frame cover 23.

95 Each body as it is brought into cylindrical form and is discharged from the final pair of rollers 224 moves upon a pair of supporting bars 261 and beneath a top guide bar 262. The top guide bar and one of the supporting bars are held in a bracket section 263 formed as an integral part of one of the guide plates 242. The other supporting bar 261 is held in a bracket 264 carried by the other guide plate 242. The conveyor chain 191 moves the reformed can body along the bars 261, 262 and from these bars the body may be removed in any suitable manner.

100 It is thought that the invention and many 40 of its attendant advantages will be understood from the foregoing description, and it will be apparent that various changes may be made in the form, construction and arrangement of the parts 45 without departing from the spirit and scope of the invention or sacrificing all of its material advantages, the form hereinbefore described being merely a preferred embodiment thereof.

105 I claim:

110 1. In a machine for reforming can bodies provided with relatively flat side parts joined by sharply curved connecting parts, the combination of a reforming matrix through which the can bodies pass, the walls of said matrix forming a substantially flat oval entrance for receiving the flat can bodies and gradually merging into a substantially circular discharge opening, these matrix walls engaging both the sharply curved parts 50 of the can bodies and the flat side parts and progressively bending the same into the desired cylindrical curvature, and conveying means for propelling said bodies through said matrix during the reforming operation.

115 2. In a machine for reforming can bodies pro-

- vided with relatively flat side parts joined by sharply curved connecting parts, the combination of means reforming said flat can bodies into desired shape, a magazine for containing said flat bodies in stack formation, and feeding means first engaging a sharply curved connecting part of a said body for removing it from the stack and thereafter engaging an edge of said body to feed it to said reforming means, and means for engaging the rear edges of the can bodies and propelling them through said reforming means.
3. In a machine for reforming can bodies provided with relatively flat side parts joined by sharply curved connecting parts, the combination of concave means reforming said flat can bodies into desired shape, a magazine for containing said flat bodies in stack formation, and means engaging a sharply curved connecting part of the lowest can body in said magazine and removing it for the reforming operation by said reforming means, and means for engaging the rear edges of the can bodies and propelling them through said reforming means.
4. In a machine for reforming can bodies provided with relatively flat side parts joined by sharply curved connecting parts, the combination of preliminarily acting reforming devices engaging within and without the flattened can body, and subsequently acting reforming devices engaging only the outer surface of the body.
5. In a machine for reforming can bodies provided with relatively flat side parts joined by sharply curved connecting parts, the combination of preliminarily and subsequently acting reforming devices, said preliminarily acting reforming devices comprising internally and externally acting pressure elements changing the curvature of said sharply curved connecting parts, and means for engaging the rear edges of the can bodies and propelling them through said reforming means.
6. In a machine for reforming can bodies provided with relatively flat side parts joined by sharply curved connecting parts, the combination of preliminarily and subsequently acting reforming devices, said preliminarily acting reforming devices comprising internally and externally acting pressure elements changing the curvature of said sharply curved connecting parts and giving a measured predetermined bow to said flat parts of said body.
7. In a machine for reforming can bodies provided with relatively flat side parts joined by sharply curved connecting parts, the combination of a magazine for holding the flat can bodies in stack formation, preliminary bending mechanism, including die members for impressing outward bows in the flat sides of the said can bodies, a reforming matrix through which the can bodies pass for the reforming operation, and feeding devices for removing single can bodies from said magazine for feeding them into said mechanism and for feeding the partially bowed can bodies to said reforming matrix.
8. In a machine for reforming can bodies provided with relatively flat side parts joined by sharply curved connecting parts, the combination of a magazine for holding the flat can bodies in stack formation, preliminary bending mechanism adjacent said magazine and including bending die members for impressing outward bows in the flat sides of the said can bodies, a reforming matrix through which the can bodies pass for the reforming operation, intermittent feeding devices operating against the sharply curved can body parts for removing single can bodies from said magazine and feeding them first to said mechanism and then to said reforming matrix, and continuously moving conveying means operating against end edges of said can bodies for propelling them into said matrix.
9. In a machine for reforming can bodies provided with relatively flat side parts joined by sharply curved connecting parts, the combination of a magazine for holding the flat can bodies in stack formation, preliminary bending mechanism, including bending die members for impressing outward bows in the flat sides of the said can bodies, a reforming matrix through which the can bodies pass in the reforming operation, feeding devices operating against the sharply curved can body parts for removing single can bodies from said magazine and for feeding them into and through said mechanism and into alignment with the entrance end of said reforming matrix, and conveying means operating at right angles to the line of travel of the can bodies while moving with said feeding devices for propelling said can bodies into and through said matrix.
10. In a machine for reforming can bodies provided with relatively flat side parts joined by sharply curved connecting parts, the combination of a reforming matrix embodying a plurality of pairs of associated elements through which the can bodies pass, the walls of successive matrix elements presenting progressive shapes from a substantially flat oval at the receiving end of said matrix to substantially a circle at the discharge end, these matrix walls progressively bending and reforming the can bodies into the desired cylindrical form, and means for passing said bodies successively through said matrix elements during the reforming operation while keeping them separated.
11. In a machine for reforming can bodies provided with relatively flat side parts joined by sharply curved connecting parts, the combination of a plurality of reforming rollers providing a reforming matrix through which the can bodies pass and by which flat can bodies are reformed into substantially cylindrical shape, actuating means for rotating said rollers at a uniform speed and means for conveying said can bodies through said reforming matrix, said means having a speed of movement which is less than the speed of rotation of said rollers.
12. In a machine for reforming can bodies provided with relatively flat side parts joined by sharply curved connecting parts, the combination of a plurality of pairs of reforming rollers providing a reforming matrix through which flat can bodies pass and by which they are reformed into substantially cylindrical shape, actuating means for rotating said rollers at a uniform speed, and means for conveying said can bodies through said reforming matrix by presenting them successively to each pair of rollers at a speed of movement which is less than the speed of rotation of said rollers.
13. In a machine for reforming can bodies provided with relatively flat side parts joined by sharply curved connecting parts, the combination of a plurality of pairs of reforming rollers providing a reforming matrix through which flat can bodies are passed for shaping into substantially cylindrical form, means for rotating said rollers at a uniform speed so that the bodies are drawn successively between each pair of rollers, and conveying means moving at a continuous speed.

speed of travel less than the speed of rotation of said rollers for transferring the can bodies from one pair of reforming rollers into those next adjacent.

5 14. In a machine for reforming can bodies provided with relatively flat side walls joined by sharply curved connecting parts, the combination of a magazine for holding the flat can bodies in stack formation, preliminary bending mechanism, including bending die members for impressing outward bows in the flat sides of the said can bodies, a reforming matrix embodying a plurality of sets of reforming rollers through which the can bodies pass and by means of which they are brought into cylindrical shape, feeding devices operating against the sharply curved can body parts for removing single can bodies from said magazine and for feeding them into and through said bending mechanism and into alignment with the said reforming rollers, and conveying means operating longitudinally of said reforming matrix and passing between each set of reforming rollers for transferring the can bodies between adjacent roller sets during the reforming operation.

10 15. A machine for reforming can bodies provided with relatively flat side walls joined by sharply curved connecting parts, the combination of a magazine for holding flat can bodies in stack formation, bending mechanism located adjacent said magazine, and including spaced die members and a pair of spaced anvils, feeding devices operating against a sharply curved can body part for removing a single can body from said magazine and for feeding it into said mechanism between said anvils and in alignment with the said die members, devices for centering said positioned can body on said anvils, actuating means for operating said die members which, in cooperation with said anvils, impress outward bows in the flat sides of the said can body, and a reforming matrix for receiving said bowed can bodies and for reforming them into the desired shape.

15 16. In a machine for reforming can bodies pro-

vided with relatively flat side parts joined by sharply curved connecting parts, the combination of preliminarily acting centering devices adapted to enter into a flat can body, and means intermediate said centering devices for bowing the flat sides of said can body, a concave elongated matrix formed of successive pairs of forming devices, and means for pushing said can bodies through said matrix.

10 17. In a machine for reforming can bodies provided with relatively flat side parts joined by sharply curved connecting parts, the combination of preliminarily acting centering devices adapted to enter into a flat can body, and means intermediate said centering devices for bowing the flat sides of said can body, said bowing means stretching the material of the body on said centering devices to increase the radius of curvature of said sharply curved connecting parts of said can body, an elongated concave matrix, and means 20 for pushing the can through said matrix.

15 18. In a machine for reforming can bodies provided with relatively flat side parts joined by sharply curved connecting parts, the combination of preliminarily acting centering devices adapted 25 to enter into a flat can body, and means intermediate said centering devices for bowing the flat sides of said can body, said bowing means stretching the material of the body on said centering devices to increase the radius of curvature 30 of said sharply curved connecting parts of said can body, and cooperating external die members.

20 19. In a machine for reforming can bodies, the combination of a series of pairs of concave reforming rolls having their concaves opposite to each other and forming an elongated concave matrix, means for rotating said rolls, and a conveyor having means for pushing the can bodies from one pair to the next pair of reforming rolls, said concave matrix varying from a flattened 35 to substantially circular form, said conveyor having a speed of movement which is less than the speed of rotation of said rolls.

JAMES A. GRAY.
